(Cl. D85—8)

To all whom it may concern:

Be it known that I, Abraham A. Sasiemi, a citizen of Great Britain, residing at 67 Wolmer Gardens, Edgware, Middlesex, England, have invented a new, original, and ornamental Design for a Pipe Stem, of which the following is a specification, reference being had to the accompanying drawing, forming part thereof:

Fig. 1 is a perspective view of a pipe stem, showing my new design;

Fig. 2 is a bottom plan view thereof;

Fig. 3 is a side elevational view thereof; and
Fig. 4 is a rear elevational view thereof.

I claim:

The ornamental design for a pipe stem, substantially as shown.

ABRAHAM A. SASIEMI.
